DISPLAY DEVICE

Charles Friedrich and Harry P. Wareham, Jr.,
Rochester, N. Y., assignors to E. E. Fairchild,
Corporation, Rochester, N. Y., a corporation of
New York

Application January 12, 1937, Serial No. 120,308

10 Claims. (Cl. 40—126)

The invention relates to a display device.

The primary object of the present invention is to provide a display device having means for supporting, holding and displaying a bottle or other receptacle and various articles and adapted to be folded around an article to be displayed and to be placed in a carton or other container for packing and shipping in such folded condition and capable, when the bottle or other article is withdrawn from the carton or other container, of automatically unfolding and opening or spreading out into display position without manual manipulation, leaving absolutely nothing for a shopkeeper or other person to do other than place the display device with its contents upon a show case, counter or other surface for display.

A further object of the invention is to provide a simple, practical and inexpensive display device which will present an ornamental appearance and be adapted to be stamped, die cut or similarly formed from a single piece of sheet material in a single operation and capable of being easily and quickly arranged to receive a bottle or other article to be displayed without the employment of separate fastening devices or similar fastening means.

A further object of the invention is to provide a display device forming a holder for a bottle or other article and open at the front for exposing such article to advantageously display the same and provided at opposite sides of its open front with display wings extending from and forming continuations of the adjacent sides or walls of the body of the display device when the same is in displaying condition and arranged to be folded over each other and over the bottle or other article to protect the latter during shipment as well as to arrange the display device in a compact condition for packing and shipping.

With the above and other objects in view, the invention consists in the construction and novel combination and arrangement of parts herein-after fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawing:

Figure 1 is a perspective view of a display device constructed in accordance with this invention and containing a bottle and arranged for displaying the same.

Figure 2 is a vertical sectional view of the same, the bottle being illustrated in dotted lines.

Figure 3 is a horizontal sectional view of the same.

Figure 4 is a horizontal sectional view showing the display device and bottle arranged within a carton.

Figure 5 is a plan view of the blank from which the display device is formed.

In the accompanying drawing in which is illustrated the preferred embodiment of the invention, the display device is formed from a blank 1 stamped or die cut from a single piece of sheet material such as cardboard, fiber board and the like having sufficient resiliency to cause the display device after being folded and arranged within a carton 2 or the container to open automatically when removed from the container and automatically assume a display condition without manual manipulation, as hereinafter fully explained.

The blank 1, which is substantially oblong, has a curved longitudinal side edge 3, which is arranged at the top of the display device when the same is set up for use, whereby the display device presents an ornamental, attractive and tapering appearance, as clearly illustrated in Figure 1 of the drawing. The blank is preferably line scored transversely at the center at 4 and at equal distances therefrom at 5 and 6 to form side walls or members 7 and 8 and display wings 9.

The blank is provided adjacent the curved side edge with spaced longitudinal parallel cuts 10 which form an integral horizontal strap 11 for engaging the neck of a bottle 12. When the display device is set up for use as shown in Figure 1, the side walls 7 and 8 are arranged substantially at right angles to each other, and the integral neck engaging strap or member 11 is bowed forward to provide a space defined by the side walls 7 and 8 and the said strap for receiving and confining the neck of the bottle. The cuts 10 preferably extend from the central score line 4 to points about midway of the side walls 7 and 8 of the blank, as clearly illustrated in Figure 5 of the drawing.

The blank is provided at the lower edge of the side wall 7 with an approximately triangular bottom member 13 and is scored longitudinally at 14 to form a hinge connection between the bottom member 13 and the said side wall 7. The bottom member 13 is provided at the side edge adjacent the side wall 8 with a hinged flap 15 which is folded upwardly on the exterior of the side wall 8 when the display device is set up for

use. The bottom member 13 is provided at its juncture with the flap 15 with a score line 16 to form a hinge connection between the flap 15 and the bottom member 13.

5 The hinged flap 15 which is approximately triangular is provided at its central apex portion with a hook 17 formed by cutting away the flap at 18 adjacent the inner or underside of the bill or projecting portion of the hook 17. The lower 10 portion of the side wall 8 is provided with a substantially V-shaped cut or slit 19, which is engaged by the hook shaped portion 17 of the hinged flap 15 when the display device is set up for use.

One or more of the score lines may or may not 15 be used, and the blank may, if desired, have short score lines 20 at the ends of the neck engaging strap 11 if desired. In setting the display device up for use, the blank is folded on the score line 14 to arrange the bottom member at right angles 20 to the side wall 7 and it is then folded on the score line 4 to arrange the side walls 7 and 8 at an angle to each other. The angle is preferably slightly less than a right angle or 90°. The flap 15 is then folded against the exterior of the side 25 wall 8, and its hook is engaged with the slit 19, which securely retains the display device in its set up or display condition. Prior to the folding of the sides 7 and 8, the bottle neck engaging strap is bowed forwardly, but this may, of course, be 30 effected after the folding and locking of the side walls.

The display wings extend outwardly from the side walls of the display device, which is open at the front to enable a bottle or other article to be 35 readily placed upon the bottom member 13 and engaged with the top strap 11, and in practice the display device will be provided at the front with suitable matter printed or otherwise placed on the display form for advertising the article or 40 product displayed.

After the bottle is placed in the display device, the wings are folded over each other across the open front of the display device and across the exposed face of the bottle to protect the latter 45 and also to arrange the display device in a compact condition to enable it to be readily placed in a carton or other container for packing and shipping. When the display device with the bottle is 50 automatically to their extended display position without any manual manipulation on the part of a storekeeper or other person, and there is absolutely nothing else to do but to remove the display device from the carton and place it upon a show 55 case, counter or other surface for display of the contents of the device.

The bottom member 13 by being formed integral with one of the side walls of the device and by being detachably interlocked with the other side 60 wall maintains the display device in a set-up display condition without the use of separate fastening devices or similar fastening means. The bottle illustrated in the accompanying drawing is substantially triangular in horizontal section 65 to conform to the configuration of the bottom member 13, but it may, of course, be of any other desired form.

What is claimed is:

1. A display device including walls in connection 70 at one side and arranged at an angle to one another forming an open front for displaying a bottle or other article, and display wings carried by said walls at opposite sides of the open front and adapted to be folded over each other at the 75 open front to permit the display device and its

contents to be packed in a container, said wings being hinged to said walls in a manner to spring away from one another whereby when the display device is removed from the container the wings will open automatically to display position 5 without manual manipulation.

2. A display device including a pair of side walls connected along their rear edges and arranged at an angle to each other to form an open front and closed back and sides, and display wings extending outwardly from the front edges of the side walls and forming continuations of the same when in a displaying condition, and said wings being foldable across the open front of the display device into compact condition to permit the same 15 and the article to be displayed to be arranged within a container, said display wings having sufficient resiliency to open automatically when the display device with its contents is removed from the container whereby the display device 20 will automatically assume a display condition without manual manipulation.

3. A display device including angular walls and forming an open front for displaying a bottle or other article and projecting display wings 25 formed integral with the said walls to overstand therefrom in the display position, said wings having resilient hinge connections with the walls and being foldable over the open front to enclose the display device and its contents for insertion within 30 a container and at the same time place said resilient connections under tension adapted to open the wings automatically to display position when the device is removed from the container.

4. A display device consisting of a blank formed 35 from a single piece of sheet material and scored to form side walls and wings arranged at the outer edges of the side walls, the scoring forming hinge connections between the walls and also between the wings and the walls to permit the 40 walls to be arranged at an angle to each other and the wings to be folded inwardly over each other, and a bottom member hinged to one of said walls and provided with means for engaging the other wall for holding the walls at an angle to each 45 other to form a body portion open at the front for the display of a bottle or other article.

5. A display device including side walls hinged together and adapted to be arranged at an angle to each other, and a bottom member hinged to 50 one of the said walls and provided with a flap foldable against the exterior of the other wall, the latter wall and the flap having coating means for securing the flap to such side wall.

6. A display device including side walls hinged 55 together and arranged at an angle to each other, one of the side walls being provided with an angularly disposed slit, and a bottom member hinged to the other side wall and provided with a flap foldable against the side wall having said 60 slit, said flap being provided with a hook-shaped portion for engaging the slit.

7. A display device including angular walls and open at the front for displaying a bottle or other article, and projecting flexible display wings in 65 foldable connection with said walls and adapted when folded to permit the display device and its contents to be packed in a container, said wings having sufficient resiliency to unfold automatically and assume displaying position when the 70 device is removed from the container.

8. A display device including a pair of angularly related walls presenting an open front for the display of an article, means in connection with said walls to engage and hold a displayed article in the 75

- angle of the walls, and wings flexibly connected to said walls to outstand therewith in display position, said wings being foldable inwardly on said flexible connections to form with the walls an enclosure for the displayed article for insertion in a container, said wings being resiliently expandable to swing outwardly and automatically assume display position upon removal of the article and its enclosure from a container. 5
- 10 9. A display device including a pair of angularly related walls presenting an open front for the display of an article, means connecting and holding the said walls and forming a supporting base for a displayed article in the angle of the 15 walls, and wings resiliently in flexible connection with said walls to normally outstand in line therewith in display position, said wings being foldable inwardly on said connections toward one another to form with the walls an enclosure for the displayed article for insertion in a container, and being automatically expansible by reason of said resilient connections to spring outwardly and automatically assume display position upon removal from a container. 5
- 10 10. In a display device, a backing member consisting of upright portions outstanding angularly with respect to one another and forming an open display front, and means to support a displayed article in the angle of said backing portions, said backing portions including end wings yieldable toward one another for folding movement across the said open front and resiliently in connection with said backing portions for creating a tension during such folding movement causing the wings 15 to spring open to normal display position when released from folded position.
